UNITED STATES PATENT OFFICE.

FRANK E. WARNER, OF WATERBURY, CONNECTICUT, AND AUGUSTUS H. COSGROVE, OF UNION HILL, NEW JERSEY, ASSIGNEES TO SCOVILL MANUFACTURING COMPANY, OF WATERBURY, CONNECTICUT, A CORPORATION OF CONNECTICUT.

TACK-FASTENED-BUTTON-ATTACHING MACHINE.

Application filed December 1, 1922. Serial No. 604,279.

To all whom it may concern:

Be it known that we, FRANK E. WARNER, a citizen of the United States, residing at Waterbury, in the county of New Haven and State of Connecticut, and AUGUSTUS H. COSGROVE, a citizen of the United States, residing at Union Hill, in the county of Hudson and State of New Jersey, have invented a certain new and useful Improvement 10 in Tack-Fastened-Button-Attaching Machines, of which the following is a full, clear, and exact description.

The object of this invention is to provide a mechanism adapted to form a part 15 of a machine for attaching or setting tack-fastened buttons, whereby the speed at which the machine may be operated may be increased without endangering the effective operation of the mechanisms of the 20 machine which perform the attaching or setting operation on the button-attaching tack within the button.

In machines of this general type with 25 which we are familiar, mechanisms are provided for substantially simultaneously feeding a single tack and a single button to a point of the machine at which the setting operation takes place. The tack is fed to 30 position upon the top of an anvil provided with a pair of cooperating spring-actuated jaws adapted to hold the tack in proper position upon the anvil, and there is a setting plunger having adjacent to it a pair of jaws 35 adapted to hold a button in position to be fed to the tack, these button-holding jaws with the button between them adapted to be moved into attaching relation to the tack by means of the plunger, and the pressure of the button upon the material to which 40 it is being attached during the attaching or setting operation functioning to depress and spread apart the tack-holding jaws out of tack-engaging relation, to thereby free the tack from its position upon the anvil and 45 permit of its removal along with the material to which the button is attached.

We have discovered that it is to some extent due to the above described automatic operation of the tack-holding jaws that it 50 has heretofore been impossible to construct a machine of this type in which a speed of operation commensurate with the manipulative speed of an operator can be practically attained, and it is to the remedying

of this particular defect that our invention 55 is primarily directed.

We have found that by positively actuating the tack-holding jaws so as to move them out of tack-holding position in proper timed relation to the button-attaching or 60 setting action of the machine, a greater speed of operation may be obtained without in any degree sacrificing accuracy or ease of operation, but, on the contrary, enhancing these qualities. 65

The invention consists in a machine for attaching or setting tack-fastened buttons, having a setting anvil and a setting plunger. A tack raceway communicates with the setting anvil and a button race- 70 way communicates with the setting plunger. Tack-holding jaws are arranged in operative relation to the anvil and button-holding jaws are arranged in operative relation to the plunger, the tack-holding jaws being positively operated to release a tack held therebetween upon the anvil in timed 75 relation to the descent of the plunger. And the invention consists further in various details of construction including manually 80 controlled means for separating the tack-holding jaws in case of failure of the button feed or other emergencies, as we will proceed now to explain and finally claim.

In the accompanying drawings illustrating 85 the invention, in the several figures of which like parts are similarly designated, Figure 1 is a side elevation of a machine embodying our invention. Fig. 2 is a front elevation thereof. Fig. 3 is an enlarged 90 fragmentary transverse vertical sectional elevation showing the main coordinated working parts embodying the invention. Fig. 4 is an enlarged front view of a portion of the machine, parts being broken 95 away to show the arrangement of the track-holding jaws. Figs. 5 and 6 show two positions of the tack-holding jaws with relation to the plunger and button-holding jaws. Fig. 7 is a rear perspective view of the carrier for the tack-holding jaws, and Fig. 8 is a front perspective view of this carrier with the tack-holding jaws mounted thereon. 100

Referring particularly to Figs. 1 and 2, 105 wherein we have shown a double machine, that is a machine having two button-setting mechanisms with their associated parts,

driven from the same source of power, 1 is the bed of the machine mounted upon legs 2, and rising from the bed are the frames 3 which carry the various operating parts 5 comprising the button-setting mechanisms and their feed hoppers, chutes and the like.

The button-setting mechanism comprises essentially a setting anvil 4 (see Fig. 3) and a setting plunger 5, the anvil being stationary and the plunger adapted to be reciprocated by means of a lever 6 mounted upon an eccentric 7 whereby the stroke of the plunger may be regulated. This lever 6 is connected with the plunger by a link 8 and is actuated through an arm 9 provided with an adjustable connection 10 and yoke 11 by a cam 12 which cooperates with a roller 13 carried by the yoke 11, the yoke 11 sliding upon a block 14 mounted upon the cam-20 carrying shaft 15. This shaft 15 is driven by gears 16 and 17 (see Figs. 1 and 2) from a back-shaft 18 illustrated as fitted with a drive pulley 19 to which power may be supplied by means of a belt from any suitable source, but obviously gear or shaft drive or other power transmission means may be used. Buttons are deposited through a feed chute 20 in a hopper 21 rotated by belt 22 and pulleys 23 and 24. The pulley 24 is 30 mounted on a countershaft 25 driven by belt 26 and pulleys 27 and 28 from back-shaft 18. The buttons are fed to a raceway 29 provided with a cut-off 30 operated through a lever 31 by a cam 32 which coacts with a roller 33 carried by the lever 31, the roller 33 being held in operative engagement 35 with the cam 32 by means of a spring 34 connected with a part of the stationary machine frame 3. The button cut-off 30 is held in normal button-interrupting relation to the chute by a spring 35 having one of its ends connected to the frame 3 and its other end connected to the cut-off 30. Operation of the cut-off 30 through the lever 31 and cam 32 will permit a button to drop down 45 into a button feed slide 36 in which operates a button pusher 37 connected through a pin 38 and slotted lever 39 with a cam 40. The face of this cam operates upon a roller 41 carried by the lever 39, and the lever is pivoted substantially midway of its length as at 50 42 upon the machine frame. Cooperating with the button feed slide 36 and normally in alignment therewith is a pair of button-holding jaws 43 mounted upon the bearing member 44 of the plunger 5, so as to be slidable in unison with the plunger 5. These jaws are of the same type as those shown in connection with the machine of the patent 55 of F. E. Stanley and G. R. Leggett, No. 1,183,822, granted May 16, 1916, and, inasmuch as they form no part of this invention, will not be further described except to say that they are adapted to spread apart after 60 having carried the button down to tack-

engaging position to thereby release the button as it is set upon an article. When the jaws are in their normal position as shown in Figs. 2 and 4, operation of the button pusher 37 will push a button out of the slide 70 36 and into the button-holding cavity formed in the jaws 43.

Tacks are supplied through a feed chute 45 to a feed hopper 46 rotated by a belt 47 and pulleys 48 and 49, the pulley 49 being carried by the countershaft 25. From the hopper 46 the tacks are fed to a tack raceway 50 provided with a cut-off 51, operated simultaneously with the operation of the button cut-off 30 by means of a lever 52 80 having a link 53 provided with a pin 54 which pin cooperates with a slot 55 in the cut-off. The lever 52 is keyed upon the shaft of the lever 31 and is operated therewith by the cam 32 through roller 33. The cut-off 51 is held normally in feed-interrupting position as shown particularly in Figs. 2 and 4 by means of a spring 56. The operation of the cut-off 51 permits a tack to be fed from the raceway 50 into a tack slide 57 leading to the setting anvil, and in this slide operates a tack pusher 58 (see Fig. 3) adapted to be reciprocated through a link 59 by means of a cam 60 which operates upon a roller 61 carried by a sliding frame 62 95 connected with the link 59. The roller 61 is held in engagement with the cam 60 by a pair of springs 63 connected with an extension 64 of the sliding frame 62 and with the frame 3 of the machine. In its reciprocation, the tack pusher 58 recedes to a point in back of the tack raceway and then advances with a tack picked up from the discharge end of said raceway until it reaches a point where the tack is positioned upon 100 the top of the anvil 4.

Mounted for vertical sliding reciprocation upon the anvil 4 is a carrier 65 having a pair of rearwardly extending lugs 66 between which operates one end of a lever 67 pivoted on a shaft 68 mounted in the frame 3. This lever carries at its opposite end a roller 69 which bears upon an internal cam 70, the roller being held in contact with the cam by means of a spring 71 passing through the bed 1 of the machine, and having its lower end fixedly attached to a stationary part of the machine (not shown). It will be seen that by this arrangement the rotation of the cam 70 will cause a vertical reciprocation of the carrier 65 relative to the anvil 4.

Mounted for pivotal action upon the carrier 65 are the tack-holding jaws 72, which lie alongside the anvil 4 and the upper ends of which are turned inwardly and provided with tack-gripping portions 72'. These jaws are held normally in tack-engaging relation by means of a spring 73 herein shown as formed of a piece of spring wire, the 130

loop end of which extends rearwardly through an aperture 74 in the frame, and is by this arrangement positioned out of the way of the operator.

5 It sometimes happens that during the operation of the machine a tack will be advanced to setting position, but there will be no button simultaneously advanced for cooperation with this tack. When this occurs, it will be necessary to remove the tack in order to prevent possible fouling or jamming of the machine, and to this end we provide a manually operated device for retracting the carrier 65 and with it the 10 tack-holding jaw 72 so as to free the tack from its position upon the anvil. This manually operated device comprises an arm 75 pivoted at 76 in a bracket 77 carried by the bed 1, and through this arm and having 15 a loose connection therewith extends a rod 78, the upper end of which is formed as a hook 79 which embraces the upper edge of the forward end of the lever 67. It will be seen that by downward pressure upon the 20 outer end of arm 75, lever 67, and with it carrier 65 and jaws 72, will be depressed and the jaws sliding over the inclined or tapered upper end 80 of the anvil 4 will separate and release the tack. During the 25 reciprocation of the carrier 65 by the action of the cam and lever mechanism, the arm 75 will be retained in its raised position, as shown in Fig. 3, by means of a spring 81.

The operation of the machine is substantially as follows:—If the tack and button chutes or either of them contain no tacks or buttons, respectively, the hoppers 46 and 21 may be rotated by hand. This hand rotation of these hoppers is permitted by 30 means of the pawl and ratchet mechanism illustrated in Fig. 1, which is upon each of the pulleys 23 and 48, and comprises a ratchet 82 and a cooperating pawl 83. This pawl and ratchet mechanism also serves to 35 prevent rotation of the hoppers in reverse direction. As the hoppers are rotated, the raceways will fill with buttons and tacks and when sufficient buttons and tacks are in the raceways, operation of the machine may be 40 started.

An ordinary pedal-operated jaw clutch is provided, so that depression of the pedal and immediate release thereof will allow the machine to function through one complete cycle and then stop. Continued depression of the pedal will permit the machine to function continuously. This type of pedal and clutch mechanism is well known and would appear to need no further 45 explanation here.

In order to set a button upon a piece of cloth, the machine is operated through a complete cycle, with the cloth positioned above or resting upon the tops of the tack-holding jaws 72, and the various operations

of the machine are as follows:—The tack and button cutoffs 51 and 30 respectively will operate simultaneously to allow a single tack and a single button to drop into position in the slides 57 and 36 respectively. 70 Then the tack pusher 58 will be advanced by the rotation of its cooperating cam 60, and the button pusher 37 will be advanced by cooperation of its lever 39 and roller 41 with cam 40, the tack will be advanced into 75 setting position upon the top of the anvil and between the tack-holding portions 72' of the jaws 72, and the button will be pushed into the button-holding cavity in the button-holding jaws 43. When the tack and button 80 are so positioned, the cam 12 will operate upon the roller 13 and through arm 9 and lever 6 will move plunger 5 downward. The plunger in its descent will carry with it 85 the button-holding jaws 43 by means of the engagement of its setting die 84 within the shank of the button. As the plunger 5 and with it the jaws and the button reach that point in its descent at which the point of the tack is just entering the shank of the 90 button (as shown in Fig. 5), the cam 70 will operate upon the roller 69 to depress the outer end of the lever 67 and thereby cause the descent of the jaw carrier 65 and with it the jaws 72, the tack holding portions 72' of which, riding over the conical end 80 of the anvil, will be separated as they are lowered and will release the tack, 95 (see Fig. 6), the plunger 5 and with it the button-holding jaws 43 and the button, continuing in their descent meanwhile and completing the setting of the button upon the material. When the setting operation is completed, the tack-holding jaws 72 will 100 rise, and their tack-engaging portions 72' 105 will engage the edges of the lower surface of the tack head and will raise the tack and with it the button and the fabric to which it is attached off of the anvil and will return to normal tack-engaging position, as 110 shown in Figs. 4 and 5.

This series of operations will be repeated in cycle as often as the clutch pedal is depressed to perform a single button setting operation each time, or, if the clutch 115 operating pedal is held depressed, the cycle of operations will be indefinitely repeated so that in the latter case, the buttons will be set upon the material to which they are to be applied in a continuous manner, but 120 spaced according to the movement imparted to the material by the operator between each completed setting operation.

It will of course be understood that all of the cams hereinbefore mentioned are 125 so positioned upon the shaft 15 as to impart proper timing to the various mechanisms which they are designed to operate.

From the above description of the operation of the machine, it will be seen 130

that there are, among others, two main features which distinguish its operation from that of other machines heretofore known designed for a similar purpose. 5 These two features are first, the releasing of the tack by the positive withdrawal of the tack-holding jaws from holding relation thereto, whereby failure of the jaws to release the tack is impossible, and, second, 10 the raising of the tack and with it the material and the set button off of the anvil by the action of the tack-holding portions of the jaws in their return to normal position. These two features and their attendant results preclude the possibility of 15 jamming of the machine during operation, and make unnecessary any exertion upon the part of the operator in moving and positioning the material on which the buttons are to be set. Moreover, as distinguished from 20 those machines previously referred to, in which pressure of the material upon the jaws is depended upon for moving them to tack-releasing position, the above-mentioned features of the invention tend to 25 lessen strain and wear upon the material and preclude the possibility of its becoming pinched or caught by the parts of the machine and its consequent tearing or defacement.

30 Although we have herein shown and described a particular embodiment of our invention, we do not consider it as limited thereto, except as hereinafter pointed out in 35 the claims.

What we claim is:-

1. In a tack - fastened - button attaching machine, a setting anvil, a setting plunger, means for supplying and positioning a tack upon said anvil, means for supplying and 40 positioning a button with respect to said plunger, and positively actuated tack-holding means mounted upon and carried by said anvil and movable relatively thereto for releasing the tack in timed relation to the setting operation of said machine.

2. In a tack - fastened - button attaching machine, a stationary setting anvil, a reciprocating setting plunger, means for supplying and positioning a tack upon said anvil, means for supplying and positioning a button with respect to said plunger, tack-holding means mounted upon and carried by said anvil movable with respect thereto, by 50 said anvil movable with respect thereto, and means for positively actuating said tack-holding means in timed relation to the reciprocation of said plunger.

3. In a tack - fastened - button attaching machine, a stationary setting anvil, a reciprocating setting plunger, means for supplying and positioning a tack upon said anvil, means for supplying and positioning a button with respect to said plunger, and a pair of positively actuated tack-holding 55 jaws mounted upon and carried by said

anvil and movable in timed relation with respect to the reciprocation of said plunger.

4. In a tack-fastened-button attaching machine, a stationary setting anvil, a reciprocating setting plunger, means for supplying and 70 positioning a tack upon said anvil, means for supplying and positioning a button with respect to said plunger, a jaw carrier carried by said anvil and movable with respect thereto and carrying a pair of tack-holding 75 jaws, and means including a cam and lever mechanism for imparting reciprocatory movement to said jaw carrier and with it said jaws in timed relation to the reciprocation of said plunger. 80

5. In a tack-fastened-button attaching machine, a stationary setting anvil, a reciprocating setting plunger, means for supplying and positioning a tack upon said anvil, means for supplying and positioning a button with respect to said plunger, a jaw carrier mounted upon and slidable with respect to said anvil and carrying a pair of spring-pressed tack-holding jaws, and means including a cam and lever mechanism for 90 imparting sliding movement to said carrier upon said anvil to impart tack releasing movement to said tack-holding jaws in timed relation to the reciprocation of said 95 plunger.

6. In a tack-fastened-button attaching machine, a stationary setting anvil, means for positioning a tack upon said anvil, a pair of tack-holding jaws mounted upon and carried by said anvil for vertical reciprocation with respect thereto and normally engaging said tack, and means for positively reciprocating said jaws, whereby upon their descent they will release said tack and upon their subsequent ascent will raise 100 said tack from said anvil.

7. In a tack-fastened-button attaching machine, a stationary setting anvil, a jaw carrier mounted for longitudinal sliding movement with respect thereto, a pair of tack-holding jaws pivotally mounted on said carrier and slidable therewith, a lever operatively connected with said jaw carrier, a cam for positively actuating said lever and through it said jaw carrier to move the same and with it said tack-holding jaws, and manually operable means comprising an arm and a link connected with said lever for manually actuating said jaw carrier independently of the operation of 110 said cam.

8. In a tack-fastened-button attaching machine, a stationary setting anvil, a reciprocating setting plunger, means for supplying and positioning a tack upon said anvil, means for supplying and positioning a button with respect to said plunger, a pair of tack-holding jaws mounted upon and carried by said anvil and adapted to normally engage the tack to hold it in position upon 115

- said anvil, and means for positively reciprocating said jaws whereby as said plunger descends carrying with it said button to perform the setting operation, said jaws will 5 be positively moved out of tack-holding position as said tack enters said button.
9. In a tack-fastened-button attaching machine, a stationary setting anvil, a reciprocating setting plunger, means for supplying and positioning a tack upon said anvil, means for supplying and positioning a button with respect to said plunger, a pair of tack-holding jaws mounted upon and carried by said anvil and adapted to normally 10 engage the tack to hold it in position upon said anvil, and means for positively reciprocating said jaws whereby as said plunger descends carrying with it said button to perform the setting operation, said jaws will be positively moved out of tack-holding 20 position as said tack enters said button and after the completion of the setting operation said jaws will be returned to tack-engaging position and during such return will raise the tack and with it the set button off 25 of said anvil.
- In testimony whereof we have hereunto set our hands this 24th day of November A. D. 1922.
